UNITED STATES PATENT OFFICE

165,476

COLLAR CLASP

William L. Mitchell, Omaha, Nebr.

Application June 14, 1951, Serial No. 15,533

Term of patent 14 years

(Cl. D17—8)

To all whom it may concern:

Be it known that I, William L. Mitchell, a citizen of the United States, residing at Omaha, in the county of Douglas and State of Nebraska, have invented a new, original, and ornamental Design for a Collar Clasp, of which the following is a specification, reference being had to the accompanying drawing, forming part thereof.

The diagonally disposed lines shown in Figure 1 represent green color.

I claim:

The ornamental design for a collar clasp, as shown and described.

WILLIAM L. MITCHELL.
